MAGNETIC SWITCH OPERATING
MECHANISM

John C. Ponstingl and Lawrence Pierce, Pittsburgh, Pa., assignors to Westinghouse Electric Corporation, East Pittsburgh, Pa., a corporation of Pennsylvania

Application July 30, 1948, Serial No. 41,494

8 Claims. (Cl. 200—87)

1

Our invention relates to electromagnetic contactors and more particularly to the electro-mechanical interlocks usually used with electromagnetic contactors and relates to improvements and additions to the subject matter disclosed and claimed in the copending application of John C. Ponstingl, Serial No. 5,358, filed on January 30, 1948 and entitled Operator for Electric Switches.

Whenever an auxiliary electric switch is to be coupled to the magnet and is to be operated by the magnetic armature in addition to the operation of the electromagnetic contactor, several problems immediately call for solution. Suitable links and lever mechanisms must be added, and such links and mechanisms as a rule provide off-center loading if the interlocks are not operated on the center line of motion of the magnet, namely, the solenoid actuated part. Such off-center loading however small introduces excessive wear on the armature guiding mechanisms.

One broad object of our invention is the provision of lever mechanisms of an electro-mechanical interlock that produces no off-center loading.

Another object of our invention is the provision of interlocks for electromagnetic contactors that require no extra mechanisms and produce no off-center loading.

Other objects of our invention will become more readily apparent from a study of the following specification and the accompanying drawing, in which:

Figure 1 is a plan view of our invention;

Fig. 2 is a side view of our invention, and

Figs. 3 and 4 are plan views of details of our invention.

In the figures of the drawing, the reference character 1 designates the base or control panel to which our device, in use, is secured. The E-shaped magnet 2 is provided with a pair of heavy laminations 3 at the outer surfaces, which laminations are provided with the flanges 4 and 5 for mounting the E-shaped magnets to the base 1.

The magnet structure is so mounted on the base 1 that the open part of the E faces downwardly, that is, the legs 6, 7 and 8 are directed down, and with the stem 9 being disposed so as to project horizontally from the base. The disposition mentioned of the parts is the usual one in use but our invention is not limited in use to the particular position shown and described. The disclosure of our device with reference to a vertical base 1 is merely illustrative.

The middle leg 7, or core, carries the energiz-

2

ing coil 10 held in place by friction or some simple readily displaceable coil holding means not constituting part of our present invention.

To the forward leg 8, we secure the generally rectangular plate 11. This plate 11 is provided with tabs, or tongues, 12 and 13 that project beyond the upper surface of the stem 9 and the lower surface of the armature 14. These tabs are slightly undercut at the junction of the tab with the main portion of the rectangular plate. The amount of undercut is such that the transverse dimension of the tab at the undercut is substantially equal or a trifle less than the distance between points 15 and 16 on the frame 17 shown in Figs. 1 and 3.

The frame 17 is constructed of very thin tough sheet metal to provide a knife edge bearing element on the tab necks when the parts are assembled as shown in Figs. 1 and 2.

The armature carrying operator is built up of two parts identical in shape. The right-hand part, or side member, 21 is a generally U-shaped flat member having outwardly directed feet 22 and 23 connected to the ends of the legs of the U. The upper foot 22 has a toe member 24 bent at right angles toward the left, as seen in Fig. 1, of the foot 22. The toe member 24 is provided with a rearwardly directed projection 25 to which certain switch elements to be operated are secured.

The lower foot 23 is provided with a toe member 26 bent at right angles toward the left of the foot 23. The toe 26 is provided with a projection, or tab, 27 bent upwardly and at right angles to the foot 26. The tab 27, when the parts are in the position shown in Figs. 1 and 2, faces in a plane parallel to the plate 11. The tab 27 is provided in its forward face at its mid-region with a cylindrical spring-positioning button not shown.

The left-hand part, or side member, 31 of the armature operator is identical in shape to the side member 21 but in assembled position with reference to side member 21, the side member 31 is turned through a half circle on a horizontal axis normal to plate 11. The left-hand part has the parts 34, 35, 36, and 37 which correspond, respectively, to elements 24 to 27 as to structure and substantially as to function.

The tabs 12 and 13 on the surfaces facing the tabs 27 and 37 are provided with spring-positioning buttons not shown.

The upper frame 17 is hooked over the tab 12 and tab 37 whereas the lower frame 17' is hooked over the tab 27 and the tab 13. A com-

pression spring 41 is disposed between the tabs 12 and 37. A similar compression spring 42 is disposed between the tabs 13 and 27. The springs 41 and 42 thus subject the frames 17 and 17' to tension and the armature carrying operator is thus held on plate 11. The elements 11, 17, 17', 21, 31, 41 and 42 thus form a unitary assembly, or armature carrying operator, that may be mounted on the E-shaped magnet as a unit. The armature carrying operator thus in structure and function may be viewed as a parallelogram construction having pivotally connected end and side members. The rigidly interconnected tabs 12 and 13 comprise one side member, the rigidly interconnected tabs 27 and 37 comprise the other side member, and the frames 17 and 17' comprise the end members.

The armature 16 is secured to the armature operating member by a suitable shaft 45 rotatably disposed in the bearings 46. From the foregoing description, it is apparent that the armature actuated parts move substantially rectilinearly, since the construction is functionally in the nature of a parallelogram having pivotally mounted side members and end members.

Further, since the frames 17 and 17' are of relatively thin material, the bearings for these frame members are substantially knife edges. Friction loss is thus a minimum.

The usual application of the type of device described in certain of the preceding paragraphs requires the addition of interlocks. In some instances a single make contact interlock suffices, whereas in other applications both a make contact and a break contact interlock are needed.

In our showing both a make contact and a break contact interlock are illustrated with the electromagnetic contactor.

We mount the interlocks 50 and 51 on the front face of plate 11. The interlock 50 is so mounted that the actuating button 52 is at the top. To actuate the button the frame 17 is provided with the extension 53. It will be noted that the extension is symmetrical with reference to the longitudinal axis of the frame 17.

When the operating members 21 and 31 move upwardly as a unit the front end, namely, the extension 53, of the frame 17, since it pivots on the tab 12, moves downwardly to operate the button 52.

The interlock 51 is mounted near the lower end of the plate 11 and the mounting is such that the button 54 is directed downwardly. To actuate the button 54 the frame 17' is provided with the extension 55. This extension 55 is disposed symmetrically with reference to the longitudinal axis of the frame. This symmetrical disposition of the extensions 53 and 55 on frames 17 and 17', respectively, produces no off-center loading on the main magnetic actuating part. The operator comprising the members 21 and 31 is thus free to oscillate in its generally vertical direction.

When the operating members 21 and 31 move downwardly as a unit, the front end of the frame 17', namely, the extension 55, moves upwardly to actuate the button 54. Further, the extensions 53 and 55 are provided with the elongated slots 57, respectively. A center line contact is thus provided on the buttons 52 and 54 and the angular position of the frames 17 and 17' does not affect the operation of the buttons.

If the interlocks 50 and 51 are alike in design, which is usually the case, then upward op-

eration of the cage will cause opening of the auxiliary circuit controlled by one interlock 50 and the closing of another auxiliary circuit which is controlled by the other interlock 51. Upon reverse operation of the cage a reverse operation of the circuits is had.

The frames 17 and 17' are identical in design, being made by the same stamping die. When only one interlock is needed, say, the upper one, then the frame 17' is in use changed end for end so that the extension 55 extends toward the rear so that no seemingly useless projections face the front.

From the foregoing it will be apparent that our interlock actuation of structure is extremely simple, involving no extra pieces that need be added either to the magnet structure, the armature, or the interlock. Further, off-center loading is entirely eliminated, thus improving the mechanical performance. Our interlock actuating device may be used with pneumatic switches, timing relays, etc., having a similar actuator as our cage.

While I have shown but one embodiment, except for the frames 17 and 17', my invention is not limited to the single showing made but is to be limited only by the scope of the claims hereto appended.

We claim as our invention:

1. In the combination of an electromagnetic switch and an electro-mechanical interlock, comprising, a magnet structure provided at its aft end with means for supporting the structure on a suitable base, an energizing coil for the magnet structure, a plate mounted on the forward end, said plate being longer than the height of the structure and so mounted on the structure that the ends thereof at each end project beyond, that is, above and below the magnet structure, an operating member including abutments disposed transverse of the upper and lower ends of the magnet structure, an armature mounted on the lower end of the operating member for actuating the operating member, an elongated frame of relatively thin flat material disposed to have its ends hooked over the upper abutment of the operating member and the upper projecting end of the plate, a similar frame at the lower end of the operating member similarly disposed between the plate and lower abutment of the operating member, two compression springs disposed respectively between the upper projection of the plate and the upper abutment and the lower projection of the plate and the lower abutment, a switch mounted on the front surface of the plate, a vertically operable button for said switch, said frame being provided with a forwardly directed extension to the front of the region of the frame hooked over the projection on the plate and positioned to actuate the button upon vertical movement of the operating member by said armature.

2. The combination of an electromagnetic contactor and an interlock switch, comprising, an E-shaped magnet structure having a stem and three legs, means on one of the outer legs for mounting the structure on a suitable base, an energizing coil on the middle leg, an armature operable by energization of said coil, a plate secured to the edge of the other outer leg, said plate projecting beyond the edge of the stem and the ends of the legs, an armature carrying operator having a pair of cross-bars, one normally disposed in spaced facing relation to one end of the

plate, and the other similarly disposed with relation to the other end of the plate, said armature being secured on the operator adjacent the cross-bar disposed in facing relation to the end of the middle leg, said operator having side members disposed in closely spaced relation to the leg carrying the plate to thus guide the operator for movement parallel to the faces of the E-shaped magnet structure, a rectangular frame of relatively thin material hooked over one end of the plate and on the cross-bar disposed in facing relation of the one end of the plate, a second similar frame similarly mounted at the other end of the plate and corresponding cross-bar, two compression springs one disposed to coact with one plate end and corresponding cross-bar and the other disposed to coact with the other plate end and the cross-bar facing this other plate end, a switch mounted on the front surface of the plate, said frame being provided with a forwardly directed extension extending to the front of the plate and being disposed to actuate the switch upon actuation of said operator.

3. The combination of an electromagnetic contactor and an interlock switch, comprising, an E-shaped magnet structure having a stem and three legs, means on one outer leg of the structure for mounting the structure on a suitable base, an energizing coil on the middle leg, an armature operable upon energization of said coil, a plate secured to the edge of the other outer leg, said plate projecting beyond the edge of the stem and the ends of the legs, an armature carrying operator having a pair of cross-bars, one normally disposed in spaced facing relation to one end of the plate and the other similarly disposed with relation to the other end of the plate, a flat projection on each cross-bar disposed in a plane substantially parallel to the plate, said armature being secured on the operator adjacent the cross-bar disposed in facing relation to the end of the middle leg, said operator having side members disposed in closely spaced relation to the leg carrying the plate to thus guide the operator for movement parallel to the faces of the E-shaped magnet structure, a rectangular frame of relatively thin material hooked over one end of the plate and on the projection on the cross-bar disposed in facing relation to the one end of the plate, a second similar frame similarly mounted at the other end of the plate and corresponding cross-bar, two compression springs one disposed to coact with one plate end and corresponding cross-bar and the other disposed to coact with the other plate end and the cross-bar facing this other plate end, said frame having a forwardly directed projection falling generally in the longitudinal axis of the frame and projecting a short distance in front of the point where it is hooked over the end of the plate, a switch mounted in the path of the projection on the frame to thus be operated by the actuation of the operator.

4. The combination of an electromagnetic contactor and an interlock switch, comprising, a magnetic base, a parallelogram construction comprising an armature carrying operator including a pair of spaced side members provided with tabs at their ends, which tabs are disposed between and in perpendicular relation to the ends of the side members, fixed tabs secured to the base respectively in facing relation to the tabs on the ends of the side members, a pair of end members in the general shape of a picture frame having their ends hooked over corresponding tabs

on the side members and base, a compression spring disposed between the tabs at one end, a similar spring similarly disposed at the other end, whereby said springs hold the parallelogram construction together as a unit, an armature secured to the operator, means for actuating the armature, a switch secured to the base on the front surface of the base, and a projection on the front end of one end member disposed over the switch and adapted to operate the switch upon actuation of said armature.

5. The combination of an electromagnetic contactor and an interlock switch, comprising a base, a parallelogram construction including a pair of side members and a pair of end members of an open frame type of thin flat material hooked over corresponding ends of the side members, two compression springs disposed respectively between corresponding ends of the side members substantially within the frame of the end members to thus hold the side members and end members together, securing means for securing one side member to the base with the inner surface facing the base, an armature secured to the other side members, coil means for actuating the armature, a switch secured to the outer surface of the one of the side members secured to the base, and a projection at the mid-portion of one of the end members disposed to actuate said switch upon energization of said coil means.

6. The combination of an electromagnetic contactor and an interlock switch, comprising, a parallelogram construction including a pair of side members and a pair of open frame end members of thin material hooked over corresponding ends of the side members, two compression springs disposed respectively between corresponding ends of the side members substantially within the frames of the end members to thus hold the side members and the end members together, a magnet structure, one of said side members being in the form of an open frame to receive the magnet structure between the edges of the frame, means securing the other side member to one end of the magnet structure in such manner that the rear surface of the side member is adjacent the magnet structure, means at the other end of the magnet structure for securing the magnet structure to a suitable base, or control panel, an armature secured at the region of one of the freely movable corners of the parallelogram construction, an energizing coil disposed on the magnet structure for actuating said armature, a switch secured to the front surface of the side member mounted on the magnet structure, a button for actuating the switch, and a projection, at the middle of the end edge of one of the end members, disposed to actuate said button upon energization of said coil.

7. In operating means for electric switching means, in combination, a base, a flat member mounted on the base and having two tabs projecting from opposite edges thereof at substantially diametrical regions of the member, an armature carrying operator in the form of an open frame having two tabs projecting from opposite ends of the operator, the dimensions of the operator and disposition of the tabs on the operator being such that when the operator is in its normal position a tab at one end of the operator is disposed in spaced facing relation to a tab at one edge of the flat member and the other two tabs on the flat member, and operators are similarly disposed with respect to each other, a rectangular open frame member of relatively

thin material hooked over one pair of facing tabs and a similar rectangular open frame member of relatively thin material hooked over the other pair of facing tabs to thus form a parallelogram type assembly, two compression springs one disposed substantially in the plane of one rectangular frame member and the other disposed substantially in the plane of the other rectangular frame member, one spring thus engaging one pair of facing tabs and the other spring engaging the other pair of facing tabs to thus subject the rectangular frame members to tension, switching means mounted on the flat member on the side remote from the position of the armature carrying operator, an extension on one of the rectangular open frame members projecting in operative relation to the switching means, whereby parallel operation of the armature carrying operator with respect to the flat member causes the extension to operate the switching means.

8. In operating means for electric switching means, in combination, a flat plate, a magnet structure, said plate being secured to the magnet structure in a vertical position, an armature carrying operator having ends when the operator is in its assembled and normal operating position disposed in parallel relation to the ends of the plate, a pair of rectangular frames each of relatively thin material and generally in the shape of a picture frame, except that one end of each frame is provided with an extension, one of the frames being hooked at one end over one end of the plate and the other end over the facing end of the operator and the other of said frames being similarly mounted at the other end of the plate and the corresponding facing end of the operator, a pair of compression springs one disposed between one end of the plate and the facing end of the operator and the other
